CLAIM

The ornamental design for a perfume bottle, as shown and described.

DESCRIPTION

1.1 is a perspective view of a perfume bottle, showing the design;

1.2 is a front elevation view of the perfume bottle of 1.1;

1.3 is a rear elevation view of the perfume bottle of 1.1;

1.4 is a right side elevation view of the perfume bottle of 1.1;

1.5 is a left side elevation view of the perfume bottle of 1.1;

1.6 is a top plan view of the perfume bottle of 1.1; and

1.7 is a bottom plan view of the perfume bottle of 1.1.

The broken lines depict portions of the perfume bottle that form no part of the claim.

1 Claim, 7 Drawing Sheets
